COACH FOR PICK-UP TRUCKS

James A. McIntosh, 950 W. 5th St., San Pedro, Calif.

Filed July 5, 1961, Ser. No. 65,811

Term of patent 3½ years

(Cl. D14—3)

FIG. 1.

FIG. 2.

FIG. 3.

FIG. 4.

FIG. 1 is a side elevational view of a coach for pick-up trucks showing my new design;

FIG. 2 is a rear elevational view thereof; and

FIG. 3 is a front elevational view thereof.

FIG. 4 is a top plan view thereof.

The truck shown in broken lines in FIG. 1 is included for illustrative purposes only.

I claim:

The ornamental design for a coach for pick-up trucks, as shown and described.
